UNITED STATES PATENT OFFICE.

ANDREW GEIBEL, OF CHICAGO, ILLINOIS.

WASHBOARD SUPPORT AND SHIELD.

No. 865,487.

Specification of Letters Patent.

Patented Sept. 10, 1907.

Application filed March 20, 1907. Serial No. 363,395.

To all whom it may concern:

Be it known that I, ANDREW GEIBEL, a citizen of the United States of America, and a resident of Chicago, county of Cook, State of Illinois, have invented 5 certain new and useful Improvements in Washboard Supports and Shields, of which the following is a specification.

The main objects of this invention are to provide a convenient, simple, durable and improved form of 10 combined washboard support and shield; to provide an improved support that will hold a washboard up above the bottom of the tub so as to permit the tub to be filled with clothes to its full capacity without interference with the usefulness of the washboard; that 15 will hold the washboard in convenient position above the sides of the tub so that the operator may work without getting her head directly over the hot steam from the tub and without bending her body to an uncomfortable position; to provide a washboard support having 20 a shield that will prevent spilling water and suds over the edge of the tub; and to provide a support that will firmly hold the board and be readily adjustable to different sizes of washboards.

A further object is to provide simple means for 25 quickly attaching or detaching the washboard from the support without the use of set screws or other projections which might engage and tear the clothing of the operator or the articles which are being washed.

These objects are accomplished by the device shown 30 in the accompanying drawings, in which:

Figure 1 is a perspective view of a washboard holder constructed according to this invention, being shown in position upon a tub and holding a washboard. Fig. 35 2 is a top plan of the holder detached from the board and tub, a portion of the shield being broken away. Fig. 3 is a side elevation without the washboard.

In the construction shown, a shield plate 1 is mounted upon a pair of bracket arms 2 and serves as a transverse member connecting said arms to form a rigid 40 support for a washboard 3. The outer edges 5 of the shield are preferably stiffened in the usual manner.

The arms 2 are disposed in parallel relation and are spaced at the same distance apart as the side-bars of the washboard to which they are to be attached. At 45 points intermediate of their ends, the arms 2 are pivotally connected to the plate by headed screws 7.

Thus, when the upper ends of said bars are drawn together, the lower ends thereof will be moved apart. To provide for attachment to washboards of different 50 widths, a plurality of pivot-holes 8 are placed for each pivot 7, along a line transverse to the bars 2. In order to hold the upper part of the plate 1 in contact with the arms 2, said arms are provided with headed screws 9, which project through transverse slots 10 in the plate 55 1. These screws may be left sufficiently loose to permit the arms to slide freely. The arms 2 are con-

nected at points above their pivots 7 by a two-piece tie rod 11 having an interposed turnbuckle 12. The parts 11 are loosely connected with lugs 11' on the arms 2 to permit of the desired freedom of movement 60 of said arms 2.

Ordinary washboards are constructed in the form illustrated in Fig. 1, except that the side-bars 13 are usually extended so as to rest upon the bottom of the tub and thereby hold the board in the right position. 65 These lower ends of the side-bars are always in the way of the operator and interfere with the speed and execution of the work. When used in connection with the device shown, the washboard frame may be cut off flush with the lower ends of the arms 2 of the 70 holder.

The lower ends of the arms 2 are provided with lugs 15 preferably integral with the inner sides thereof, so as to fit between the inner sides of the washboard bars 13, forming shoulders against which the board may rest 75 and preventing the board from slipping into the tub 4. The upper ends of the washboard bars are engaged by lugs 16 at the outer sides of the upper ends of the arms 2. By turning the turnbuckle 12 in the proper direction, the upper lugs 16 are forced inwardly against 80 the sides of the washboard, while the lower lugs 15 are forced outwardly against the inner sides of the bars 13, until the washboard is firmly secured to the holder.

Each arm 2 is provided with a depending fork or clamp comprising the opposed jaws 17 and 18, the 85 outer one of which is provided with a thumbscrew 19. These clamps are adapted to fit over the side of a tub and support the washboard and shield in an inwardly inclined position, as shown. The bracket arms 2 with their clamps 17 and lugs 15 and 16 are preferably of 90 cast metal and the shield is of sheet metal.

In operation, the arms 2 are adjusted for any particular washboard by shifting one or both of the screws 7 so that the arms may underlie the side bars of the washboard. The turnbuckle is then rotated until the 95 board is firmly clamped between the lugs 15 and 16. The board with its support as a whole may then be placed over the rim of a tub and attached or detached by merely turning the thumbscrews 19.

What I claim as my invention and desire to secure 100 by Letters Patent is:

1. A washboard holder, comprising a frame, having means for attaching it to the side of a wash-tub, a shield mounted on said frame, being inclined toward the tub and extending across the rim thereof, and movable clamping 105 lugs for detachably mounting a washboard above said shield.

2. A washboard holder comprising a frame, a forked clamp adapted to straddle the rim of a wash-tub for securing said frame to the side of such wash-tub, adjustable 110 clamping means on said frame for rigidly holding a washboard in an elevated inwardly inclined position across the rim of the tub, and a shield on said frame for conducting into the tub drippings from said washboard.

3. In a washboard holder, the combination of a support comprising a shield plate and means for attaching it to the rim of a wash-tub in an inwardly inclined position, a projection on said support adapted to engage the lower edge of a washboard for supporting it clear of the bottom of the tub, and a clamp on said support for detachably securing said board against lateral shifting thereon.
4. In a washboard holder, the combination of a support comprising a shield plate and means for attaching it to the rim of a wash-tub in an inwardly inclined position, a projection on said support adapted to engage the lower edge of a washboard for supporting it clear of the bottom of the tub, and a pair of shoulders on said support, spaced apart laterally and adapted to engage opposite side edges of the washboard; one of said pair of shoulders being adjustable toward and away from the other.
5. A washboard support comprising a pair of arms connected together, each being forked so as to straddle the rim of a wash-tub and having an inclined upper surface for supporting a washboard, and shoulders on said arms adapted to engage the sides of a washboard supported by said arms and adjustable toward and away from each other for securing the washboard against shifting.
6. A washboard holder comprising a pair of arms, a transverse member connecting them, clamps for attaching said arms to a tub, said arms being pivotally connected to said transverse member and spaced to underlie the sides of a washboard, shoulders on said arms for engaging the sides of such washboard, and means for drawing said arms together to cause said shoulders to grip the board.
7. A holder for washboards provided with side bars, comprising a transverse member, a pair of arms each pivotally connected to said transverse member and spaced to underlie the side bars of the washboard, means for shifting one of said pivotal connections toward or from the other, said arms being provided with clamps for attachment to a tub, means at one side of the pivotal axes of said arms for engaging the outer sides of the bars of the washboard, means at the other side of their pivots for engaging the inner sides of said bars, and means for swinging said arms in opposite directions on their pivots to clamp the washboard between them.
8. A holder for washboards provided with side bars, comprising a transverse member, a pair of arms each pivotally connected to said transverse member and spaced to underlie the side bars of the washboard, said arms being provided with clamps for attachment to a tub, means at one side of the pivotal axes of said arms for engaging the outer sides of the bars of the washboard, means at the other side of their pivots for engaging the inner sides of said bars, and means for swinging said

arms in opposite directions on their pivots to clamp the washboard between them.

9. A washboard holder comprising a transverse member, a pair of arms each pivotally connected to said transverse member and spaced to underlie the sides of a washboard, said arms being provided with clamps for attachment to a tub, a lug upon the inner side of the lower end of each arm; a lug upon the outer side of the upper end of each arm for engagement with the sides of a washboard; and means for drawing together the outer ends of said arms.

10. A washboard holder comprising a transverse member, a pair of arms each pivotally connected to said transverse member and spaced to underlie the sides of a washboard, means for shifting one of said pivotal connections toward or from the other, said arms being provided with clamps for attachment to a tub, a lug upon the inner side of the lower end of each arm, a lug upon the outer side of the upper end of each arm for engagement with the sides of a washboard; and means for drawing together the outer ends of said arms.

11. A washboard holder comprising a transverse member, a pair of arms pivotally connected to said transverse member and spaced to underlie the sides of a washboard, said arms being provided with tub-clamps, means at one side of the pivots of said arms for engagement with the side bars of the washboard; and a turnbuckle interposed between said arms and adapted to force said means into clamping engagement with the washboard.

12. A washboard support, comprising a shield plate, a pair of arms each pivotally connected to the lower face of said plate, said arms being spaced to underlie the sides of a washboard, said arms being provided with clamps for attachment to a tub, means at one side of the pivots of said arms for engaging the side bars of the washboard, and means for drawing together adjacent ends of said arms.

13. A washboard support, comprising a shield plate, a pair of arms spaced to underlie the side bars of a washboard, being pivotally connected to said plate adjacent to its lower edge and having sliding connection therewith adjacent to its upper edge, a lug upon the inner side of the lower end of each arm, a lug upon the outer side of the upper end of each arm, and means for drawing the upper ends of said bars toward each other.

Signed at Chicago, this 18th day of March, 1907.

ANDREW GEIBEL.
